UNITED STATES PATENT OFFICE.

JOHN W. GEARHART, OF FRESNO, CALIFORNIA.

BLANK-BOOK COVER.

1,105,506.

Specification of Letters Patent. Patented July 28, 1914.

Application filed March 18, 1913. Serial No. 755,191.

To all whom it may concern:

Be it known that I, JOHN W. GEARHART, a citizen of the United States, residing at Fresno, in the county of Fresno and State 5 of California, have invented new and useful Improvements in Blank-Book Covers, of which the following is a specification.

This invention relates to covers for blank books of the type shown in application for 10 Letters Patent, Serial Number 745,000, filed by me on Jan. 29, 1913, and wherein is included a clamp adapted to receive a filling, covers hingedly connected with said clamp and means whereby one side member of the 15 cover is locked in fixed relation to the filler clamp, while the other side member of the cover is free to move, the construction being such that when the book is placed on a table or other support in readiness for use, 20 the top member of the cover will be free to move and that, when the book is reversed, the cover member previously free to move and which is now the bottom member will become locked with respect to the filler 25 clamp, while that cover member which is now on top will be free to move.

The principal object of the present invention is to produce novel and efficient means whereby one side member of the cover is 30 locked in fixed relation to the filler clamp, which constitutes the back of the book, while the other cover member is free to move.

A further object of the invention is to 35 improve the construction of the filler clamp to form a casing for the lock mechanism.

With these and other ends in view which will readily appear as the nature of the invention is better understood, the same consists in the improved construction and novel 40 arrangement and combination of parts which will be hereinafter fully described and particularly pointed out in the claims.

In the accompanying drawings has been 45 illustrated a simple and preferred form of the invention, it being, however, understood that no limitation is necessarily made to the precise structural details therein exhibited, but that changes, alterations and modifications within the scope of the claims may be 50 resorted to when desired.

In the drawings, Figure 1 is a perspective view illustrating a blank book cover constructed in accordance with the invention, the side members of the cover being 55 folded or closed. Fig. 2 is a perspective detail view showing the top cover member

raised to a position substantially at right angles to the book. Fig. 3 is a sectional detail view taken vertically through the back of the book cover substantially on the line 60 3-3 in Fig. 5, and showing the position assumed by the locking members when the top member of the cover is closed. Fig. 4 is a sectional view similar to Fig. 3, but showing the position assumed by the locking 65 members when the top member of the cover is lifted in the act of opening the same. Fig. 5 is a horizontal sectional view taken on the line 5-5 in Fig. 3. Fig. 6 is a vertical sectional view taken on the line 6-6 in Fig. 4. 70 Fig. 7 is a perspective detail view of one of the locking members. Fig. 8 is a perspective detail view of one of the pintles.

Corresponding parts in the several figures are denoted by like characters of reference. 75

The filler clamp 10 is made of a piece of sheet metal of suitable gage to supply ample strength and rigidity for the purpose desired, and the strip of sheet metal constituting the clamp is terminally bent to present 80 hooks 11 adapted to engage notches 12 in the blank book A which constitutes the filler. Said blank book, as illustrated in Fig. 2, is provided with a cover 13 which may be of ordinary cardboard, and the 85 leaves of the filler are weakened, as indicated at 14, in accordance with the construction shown in a patent previously granted to me, the purpose of thus weakening the leaves being to cause them to lie flat when turned 90 over.

The strip of metal constituting the filler clamp 10 is provided at its upper and lower edges with lugs or wings 15 which are bent rearwardly and in the direction of each 95 other, until the free edges of said lugs meet or abut on one another, said abutting edges being secured together along the meeting line 16, see Figs. 1 and 6, by electric welding or in any other convenient manner, so 100 that the said wings or lugs 15 with the body strip 10 will constitute a casing within which the working parts of the device are accommodated. Secured on the back of the body strip, adjacent to the ends of the casing 105 formed by the lugs or wings 15, are bearing blocks 17, 17', each of said bearing blocks being firmly secured by a fastening member, such as a screw or rivet 18, by welding or in any other suitable manner. 110

The side members B of the book cover each includes a plate 19 of sheet metal, each

of which is provided at one end adjacent to the side edges thereof with hinge sleeves 20, 20', said sleeves being formed by suitably bending or coiling lugs or extensions 21, 21' of said sheet metal plate, said lugs or extensions being clearly seen in Figs. 4 and 6. In the sleeves 20 of the two cover members, which are directly opposed to each other, pintles 22 are firmly secured, preferably by means of electric welding, although for the purpose of indicating the mechanical connection between the parts, fastening members in the nature of pins 23 have been shown connecting the sleeves with the pintles. The latter, which extend beyond the sleeves, extend through bearings formed by transverse bores 24 in the block 17, and the extremities of said pintles are threaded, the two pintles being provided, respectively, with right and left hand threads 25. These threaded extensions of the pintles are in engagement with correspondingly threaded sleeves 26 carried by the locking members C, each of said locking members including a pindle 27 that extends into a bearing formed by a bearing 28 in the block 17', the pindle members being connected with the sleeves by diagonal or obliquely disposed bars 29, said bars being disposed crosswise with respect to each other, and each being recessed on its meeting face to accommodate the other bar. The recesses in the meeting faces 30 of said bars will permit the locking members to slide freely with respect to one another. Each of the pindle members 27 is provided at the extremity thereof which extends within one of the bores 28 with a notch 31.

The hinge sleeves 20' of the two cover members are provided with pintles 32 which are firmly connected therewith by welding or by fastening means, such as pins 33. Each pindle member 32 extends through the sleeve 20' within one of the bores 28 of the proximate block 17', and each of said pindle members 32 is equipped with a slidably supported spring actuated lug 34 adapted to engage the notch 31 of the proximate pindle member 27. The parts are so proportioned that normally when the side members of the book cover are closed, the lugs 34 will barely project into the recesses 31, and said lugs are, moreover, rounded, as clearly seen in Fig. 8, so as to be readily retracted when one of the book covers is raised or thrown open. Each lug 34 is carried by a stem 35 which is seated in a socket 36 in one of the pindle members 32, said socket also containing a spring 37, whereby the stem 35 carrying the lug 34 is normally forced outward. The pindle member 35 is, moreover, bifurcated, as shown at 38, to accommodate the lug 34; means such as a transverse pin 39 being provided to assemble the parts.

It will be seen from the foregoing that the locking members C are accommodated in the housing formed by the body strip 10 and the lugs or wings 15, together with the blocks 17. Each cover member has associated therewith a pindle 22 and a pindle member 32, the latter being adapted to coöperate with the pindle member 27 of one of the locking members C. Normally, when the side members of the book cover are closed upon the filler, the locking members C are retracted with respect to the block 17 through which the pintles 22 of the cover members extend. When the book is laid down flat on a table or other support and one cover member is raised, as seen in Fig. 4, the corresponding locking member C will be forced in the direction of the block 17, and it will be obvious that owing to the position of the book, the locking member which is actuated will have its pindle member 27 extending within the bore 28 of the block 17', which at the time is lowermost, or adjacent to the bottom cover member. In the act of raising the top cover member, the pindle member 32 associated therewith will be turned about its axis, and the lug 34 will thus be turned at an angle to the recess 31 in the opposed pindle member 27. At the same time the pindle member 27 of the locking member C which is being projected by the action of the screw threaded pindle associated with the top cover will receive the lug 34 of the opposed pindle member 32 within its recess 31, and the lug 34 being non-rotatable about its axis will thus enter into locking engagement with the opposed pindle member of the locking member C which has been projected. It will be seen, then, that the bottom member of the cover with which the pindle 22 and the pindle member 32 are pivotally connected will become locked with respect to the back of the book cover which is formed of the filler clamp having the housing that contains the locking devices.

Having thus described the invention, what is claimed as new, is:

1. In a book cover, a back member consisting of a sheet metal body constituting a filler clamp, said body being provided with wings bent toward each other and connected together to form a housing, and locking devices in said housing, 115
2. In a book cover, a back member consisting of a sheet metal body provided along its upper and lower edges with wings, said wings being bent toward each other and connected together to form a housing, locking devices in said housing, and hinged side members adapted to be engaged by the locking members, 125
3. In a book cover, a back member consisting of a sheet metal body having oppositely extending wings, said wings being bent to- 130

ward each other and connected together to form a housing, bearing blocks secured on the back member adjacent to the housing formed by the wings, and locking members 5 in said housing.

4. In a book cover, a back member constituting a filler clamp and a housing, bearing blocks secured on the back member and each provided with transverse bores, side 10 cover members having sleeves, pintles secured in the sleeves and engaging the bores of the blocks, and locking devices within the housing.

5. In a book cover, a back member having 15 a housing, bearing blocks secured on the back member and having transverse bores, locking members within the housing, said locking members including diagonal cross bars each having a notched pintle member 20 extending within a bore of the proximate bearing block, and a screw threaded sleeve positioned adjacent to the other bearing block, side cover members provided with sleeves adjacent to the respective bearing 25 blocks, a pintle seated in a sleeve of each side member and having a threaded end extending through a bore of the proximate bearing block and engaging the threaded sleeve positioned adjacent thereto, and pintle members secured in other sleeves of the side members and extending within bores of the proximate bearing block in the direction of the 30

notched pintle members of the locking members, said pintle members which are secured in the sleeves of the side cover members being provided with slidable spring projected 35 members.

6. In a book cover, a back member, bearing blocks associated therewith and each having two transverse bores, side cover members having pintles engaging said bores and projecting in the direction of each other, and slidably disposed locking members actuated by a pintle of one cover member and adapted 40 for locking engagement with a pintle of the 45 other cover member.

7. In a book cover, a back member having bearing blocks each provided with two transverse bores, pintles supported for rotation in said bores, side cover members each having fixed connection with two pintles, and slidable locking members supported intermediate the bearing blocks, each of said locking members having threaded connection 50 with a pintle of a cover member and adapted 55 for locking engagement with a pintle of the other cover member.

In testimony whereof I affix my signature in presence of two witnesses.

JOHN W. GEARHART.
